EPILATOR

Robert Tapper, 7621 Hampton Ave., Los Angeles, Calif.

Filed Mar. 19, 1962, Ser. No. 69,318

Term of patent 14 years

(Cl. D83—12)

FIG. 1 is a side elevational view of an epilator showing my new design, the side not shown being substantially the same in appearance;

FIG. 2 is a front elevational view thereof with the tweezers member omitted for ease of illustration.

FIG. 3 is a front elevational view of the epilator according to FIG. 1;

FIG. 4 is a side elevational view of the epilator, with the tweezers shown removed from the body portion.

FIG. 5 is a top plan view of the epilator according to FIG. 1.

I claim:

The ornamental design for an epilator, as shown and described.
